UNITED STATES PATENT OFFICE.

RICHARD SMITH, OF PHILADELPHIA, PENNSYLVANIA, ASSIGNOR TO
MACKELLAR, SMITHS & JORDAN, OF SAME PLACE.

DESIGN FOR PRINTING-TYPE.

Specification forming part of Design No. 6,351, dated January 21, 1873.

To all whom it may concern:

Be it known that I, RICHARD SMITH, (assignor to MACKELLAR, SMITHS & JORDAN,) of the city and county of Philadelphia, Pennsylvania, have originated and produced a new and original Design for Printing-Type, of which the following is a specification:

The nature of my design is fully represented in the accompanying typographic impression, to which reference is made.

What I claim as new is—
The design for printing-type, as herein shown.

RICHARD SMITH.

In presence of—

J. H. HANKMAN,
JAS. G. BERKHEIMER.
